UNITED STATES PATENT OFFICE.

JOHN H. PETTIT, OF GREAT FALLS, MONTANA.

EMBROIDERY-HOLDER.

1,242,972.

Specification of Letters Patent. Patented Oct. 16, 1917.

Application filed April 20, 1915. Serial No. 22,659.

To all whom it may concern:

Be it known that I, JOHN H. PETTIT, a citizen of the United States, residing at Great Falls, in the county of Cascade and 5 State of Montana, have invented new and useful Improvements in Embroidery-Holders, of which the following is a specification.

An object of the invention is to provide a simple device for use in connection with 10 embroidery and materials to be embroidered, and in which the material to be embroidered will be held in tension so as to permit of readily embroidering the material.

The invention contemplates, among other 15 features, the provision of a device which can be readily operated to secure a sheet of material or a portion thereof in tension so as to permit of embroidering the same, and to this end use is made of a ring and a band-like member encircling the ring, with the portion of the material to be embroidered interposed between the ring and band-like member, and means for holding the band-like member tightly against the ring to secure and hold the material in the desired 25 tension.

In the further disclosure of the invention reference is to be had to the accompanying drawings, constituting a part of this specification, 30 in which similar characters of reference denote corresponding parts in all the views, and in which:

Figure 1 is a fragmentary perspective view showing a piece of material applied to 35 my device and ready to be embroidered;

Fig. 2 is a vertical sectional view taken through the structure shown in Fig. 1;

Fig. 3 is a perspective view of the ring.

Fig. 4 is a plan view showing the band 40 detached from the ring member.

Referring more particularly to the views, I provide an annular ring 10 which is of a channel shape in cross section to form a groove 11, a band member 12 being provided 45 and preferably formed of a single piece of wire bent in a circle and having its ends terminating in diametrically outwardly extending shanks 13, with knobs 14 on the extremities of said shanks, one of said shanks 50 being slightly bent upwardly and the other slightly bent downward so that the shanks can be interlocked and the knobs retain the shanks in interlocked position, as shown.

In the use of the device described a sheet 55 of material 15 is placed over the ring 10,

after which the band member 12 is arranged to encircle the ring and loosely lie in the groove 11 into which a portion of the sheet of material is slightly pressed by the application of the band member to the ring. Now 60 upon drawing the shanks 13 together and engaging the knobs so as to interlock the shanks with one crossing the other and the knobs in superposed relation, it will be seen that the diameter of the band member will 65 be decreased so that the same will fit tightly in the groove and bind the sheet of material lying in the groove therein. At the same time the tightening of the band member in the manner mentioned, in the ring 10, will 70 also tend to pull the sheet of material slightly so as to increase the tension thereof within the circumference of the ring 10, the sheet of material being now in a position to permit of easily embroidering a monogram, 75 initials or other suitable matter thereon.

Having thus described my invention, I claim:

1. In an embroidery holder, the combination with a ring providing a continuous 80 groove, of a band member encircling the ring, shanks formed with the band member, and knobs on the free ends of the shanks, said shanks being adapted to be drawn together and held in interlocked relation by 85 said knobs to reduce the diameter of the band member and cause the same to lie in the groove of the ring, one of said shanks being bent upwardly and the other said shank being bent downwardly to facilitate the engagement of said shanks and the holding of 90 said shanks in cross relation and contacting with one another by the engagement of said knobs.

2. An embroidery holder embodying a 95 channel like ring providing an annular groove, a member encircling the ring, diametrically extending shanks formed by the ends of the band member, said shanks being bent slightly in opposite directions and 100 adapted to be drawn toward each other so that one shank will overlie the other, and knobs on said shanks to hold said shanks in overlying engagement.

In testimony whereof I affix my signature 105 in presence of two witnesses.

JOHN H. PETTIT.
